UNITED STATES PATENT OFFICE.

CHARLES E. KIELLEY, OF SUPERIOR, WISCONSIN, ASSIGNOR OF TWENTY-FIVE AND ONE-HALF PER CENT TO JOHN L. McMAHON, OF MILWAUKEE, WISCONSIN, AND TWENTY-FIVE AND ONE-HALF PER CENT TO FRED O. BRANDT, OF ST. PAUL, MINNESOTA.

RAIL CLAMP.

Application filed August 8, 1924. Serial No. 730,936.

To all whom it may concern:

Be it known that I, CHARLES E. KIELLEY, a citizen of the United States, residing at Superior, in the county of Douglas and State of Wisconsin, have invented certain new and useful Improvements in Rail Clamps, of which the following is a specification, reference being had therein to the accompanying drawing.

10 This invention relates to rail clamps and has particular reference to a clamp or holding device for traveling cranes or other large superstructures such as coal dock derricks, bridges, or the like, adjustably mounted upon railroad rails.

15 The principal object of the invention is to provide a simple and efficient form of rail clamp or securing means for such structures.

20 Another object is to provide means whereby such a device when in clamped engagement with the rail is positively secured against longitudinal movement thereupon.

25 Still another object is to provide simple means for both applying and releasing the clamp, and one that when released laterally from the rail will also be raised vertically freeing same.

30 Other objects and advantages will appear in the further description of the invention.

Referring now to the accompanying drawings forming part of this application and in which like reference characters indicate like parts:

35 Figure 1 is an elevation of one embodiment of the improved rail clamp as viewed longitudinally of the rail;

Figure 2 is a side elevation of Figure 1;

40 Figure 3 is a view similar to Figure 1, but reduced in scale, illustrating a modified arrangement of the clamping member;

Figure 4 is a side elevation of Figure 3;

Figure 5 is a perspective view of improved rail construction; and

45 Figure 6 is a perspective view of one of the gripping jaws of the clamping member.

1 represents the improved form of rail upon which the superstructure, as indicated at 2, is carried, there being shown, in Figures 3 and 4, common wheel construction for such purpose, the particular arrangement of which does not constitute part of my present invention.

3 represents a horizontally disposed shaft, which, in the preferred arrangement of the clamping member, is disposed parallel with and directly above the rail 1, and 4 represents that portion of the superstructure in which the shaft is mounted. From this shaft depend the two pendulum like members 5 and 6, their upper ends being alternately recessed and engaged upon the shaft as clearly shown in Figure 2, so that each member may be moved pivotally independently of the other on the shaft. Spaced 65 within the lower portion of the member 6 are a plurality of vertically elongated rectangularly shaped openings 7, while in the member 5 are identical openings 8. Through these openings extend the links or arms 9, 10 and 11, they being pivotally mounted upon the shaft 12 in the knuckle 13 of the member 5, and at their opposite ends are mounted upon the shaft 14 outboard of the convex portion 15 of the member 6. The 70 arms 9 and 11 extend considerably beyond the shaft 14 and are carried by the short shaft 35, which extends through their extreme ends, and pivotally engaged within the lower extremities of the depending operating members 16. Thus when the operating members 16 are raised and lowered, the shaft 14 will also be raised and lowered, carrying with it the arms 9 and 11 directly, and the arm 10 indirectly, as the latter is 75 mounted only upon the shaft 14, it preferably not being directly connected to the shaft 35.

80 Mounted upon the shaft 14 are four spaced rollers 17, they bearing against the concaved surface of the member 6, and roll freely thereupon when the shaft 14 is raised or lowered for forming as nearly as possible a non-frictional engagement with the surface of said member 6. To one end of the shaft 14 is attached the link or pitman 18 which extends upwardly to the crank arm 19 carried upon the shaft 3, said pitman and crank arm being pivotally united as at 20. The 85 crank arm 19 is securely fixed to the shaft 3 so that when the former is raised or lowered it will rotate the latter, and in the bearing for the shaft 3 is mounted an eccentric sleeve 21, the same being rigidly attached to the shaft so as to rotate with the latter, there being one of such eccentric sleeves 90

95

100

105

mounted upon either end of the shaft. When said shaft is rotated it will be slightly raised or lowered so that when the shaft 14 is raised by manipulation of the operating levers 16 it will rotate the shaft 3 and thereby slightly raise same, lifting the clamping members 5 and 6, freeing same from the top of the rail simultaneously with the lateral freeing of the jaw portions of the clamping members 5 and 6.

The jaw portions of the clamping members 5 and 6 are recessed as at 22 to receive the removable jaws 23, these latter being of harder material than that of which the members 5 and 6 are composed and which may be renewed or removed for repair from time to time without the expense and time incident to further dismantling of the clamp. These removable jaw members 23 are adequately flanged at either end as at 24 so as to be held snugly in place, and may be provided with temporary tap screws or pins as at 25. The lower inwardly projecting corner 26 of each jaw 23 is corrugated or notched as at 27, said notches registering with like notches 28 in the lower corners of the bulb of the rail 1; this being considered a novel form or shaping of rail to prevent longitudinal movement of a clamp attached thereto, it positively insuring against the movement of the clamp even when slightly insecurely clamped thereupon.

However, from the above description, it is apparent that by the depressing of the levers 9, 10 and 11 to anywhere near their ultimate clamping position, the pressure of the jaws of the members 5 and 6 is greatly augmented and made positive by the rollers 17 traversing the inclined convex surface of the member 6.

In Figures 3 and 4 I have illustrated the clamp suspending shaft 3' as being transverse the rail 1, the object being to illustrate how such a modification may be accomplished without departing from the spirit of the invention, and in these two views I have shown a modified form of operating lever indicated at 29 which is controlled by the bell-crank lever 30, the same being for the purpose of opening and closing the clamping members 31 and 32, which correspond to the clamping members 5 and 6 in the other views. In Figure 3 I have shown a bracing member 33 pivotally mounted as at 34 in the superstructure 2 for bracing the rail clamp longitudinally of the rail.

From the foregoing it is evident that I have provided an exceedingly simple and

efficient rail clamping means which when applied to the rail even in a slight degree 60 will insure positive anchorage of the superstructure to which it is attached, and one that if not positively adjusted to the contrary will remain securely attached to the rail. 65

Having thus described my invention, what I claim and desire to secure by Letters Patent, is:

1. An anchoring means for portable superstructures carried upon railroad rails 70 comprising a shaft carried by the superstructure above the rail, two opposed pendulum clamping members pivotally carried upon the shaft, said members extending downwardly upon either side of the ball of the supporting rail, means carried by one member and extending through the other member above the rail and means carried outboard of the last mentioned member for simultaneously adjusting said members to 80 or from the rail.

2. An anchoring means for portable superstructures carried upon railroad rails comprising a shaft carried by the superstructure above the rail, two opposed pendulum clamping members pivotally carried upon the shaft, said members extending downwardly upon either side of the ball of the supporting rail, means carried by one member and extending through the other member above the rail and means carried outboard of the last mentioned member 85 and cooperatively connected with said first mentioned means for simultaneously adjusting 90 said members to or from the rail. 95

3. An anchoring means for portable superstructures carried upon railroad rails comprising a shaft carried by the superstructure above the rail, two opposed pendulum clamping members pivotally carried 100 upon the shaft, said members extending downwardly upon either side of the ball of the supporting rail, means carried by one member and extending through the other member above the rail, means carried outboard of the last mentioned member and cooperatively connected with said first mentioned means for simultaneously adjusting 105 said members to or from the rail, and means cooperatively connected with said adjusting 110 means for simultaneously raising or lowering the jaws.

In testimony whereof I hereunto affix my signature.

CHARLES E. KIELLEY.
